US00D396846S

United States Patent [19]

Nakayama et al.

[11] Patent Number: Des. 396,846

[45] Date of Patent: **Aug. 11, 1998

[54] SEMICONDUCTOR DEVICE

[75] Inventors: **Masao Nakayama; Yukio Nakamura**, both of Osaka; **Isamu Yuasa; Noboru Yoshida**, both of Okayama; **Katsuji Tara**, Kyoto; **Toshio Fujiwara**, Okayama, all of Japan

[73] Assignee: **Matsushita Electronics Corporation**, Osaka, Japan

[**] Term: 14 Years

[21] Appl. No.: 69,444

[22] Filed: Apr. 16, 1997

[51] LOC (6) Cl. 13-03

[52] U.S. Cl. D13/182

[58] Field of Search D13/182; 174/52.4, 174/52.5; 257/690; 361/752, 798, 820

[57] CLAIM

The ornamental design for a semiconductor device, as shown.

DESCRIPTION

FIG. 1 is a perspective view of the top, front and left side of a semiconductor device showing our new design;

FIG. 2 is a perspective view of the bottom, rear and right side thereof;

FIG. 3 is a front elevational view thereof;

FIG. 4 is a top plan view thereof;

FIG. 5 is a left side elevational view thereof;

FIG. 6 is a right side elevational view thereof;

FIG. 7 is a rear elevational view thereof; and,

FIG. 8 is a bottom plan view thereof.
